US0D1047206S

(12) **United States Design Patent** (10) Patent No.: **US D1,047,206 S**
(45) Date of Patent: ** Oct. 15, 2024

(54) **MASSAGE DEVICE**

(71) Applicant: **Therabody, Inc.**, Los Angeles, CA (US)

(72) Inventors: **Jaime Sanchez Solana**, Los Angeles, CA (US); **Eduardo Merino**, Los Angeles, CA (US); **Zenger Zhou**, Shenzhen (CN); **Lymond Lin**, Shenzhen (CN); **David Lu**, Shenzhen (CN); **Phil Huang**, Shenzhen (CN)

(73) Assignee: **Therabody, Inc.**, Los Angeles, CA (US)

(**) Term: **15 Years**

(21) Appl. No.: **29/911,827**

(22) Filed: **Sep. 8, 2023**

(51) LOC (14) Cl. **24-01**

(52) U.S. Cl.

USPC **D24/215**

(58) **Field of Classification Search**

USPC ..... D24/215, 200, 211, 212, 213, 214, 133, D24/107, 231; D8/61; D28/12, 13 CPC A61H 7/00; A61H 7/003; A61H 7/004; A61H 7/005; A61H 9/00; A61H 15/00; A61H 2015/0007; A61H 2015/0042; A61H 2015/0071; A61H 15/0078; A61H 15/0085; A61H 15/0092; A61H 23/00; A61H 23/02

(57)

CLAIM

The ornamental design for a massage device, as shown and described.

DESCRIPTION

FIG. 1 is a top front isometric view of a massage device showing the claimed design;

FIG. 2 is a bottom rear isometric view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines in the figures show portions of the massage device that form no part of the claimed design.

1 Claim, 8 Drawing Sheets
